[57] CLAIM

The ornamental design of a top or bottom rail for outdoor railing systems, as shown and described.

DESCRIPTION

FIG. 1 is a top view of a top or bottom rail for outdoor railing systems in accordance with the invention.

FIG. 2 is a side view of the top or bottom rail for outdoor railing systems illustrated in FIG. 1.

FIG. 3 is a view of the inwardly disposed face of the top or bottom rail for outdoor railing systems illustrated in FIG. 1 illustrating spindle recess configurations in dashed lines for illustrative purposes only and form no part of the claimed design.

FIG. 4 is an end view of the top or bottom rail for outdoor railing systems illustrated in FIG. 1.

FIG. 5 is an enlarged end view of the top or bottom rail for outdoor railing systems illustrated in FIG. 1.

FIG. 6 is a perspective view of the top or bottom rail for outdoor railing systems illustrated in FIG. 1 particularly illustrating the profile and inwardly disposed face thereof; and,

FIG. 7 is a perspective view of the top or bottom rail for outdoor railing systems illustrated in FIG. 1 particularly illustrating the profile and upper surface thereof.
